UNITED STATES PATENT OFFICE.

JAMES T. HUTTON, OF FARMINGTON, NEW MEXICO.

CHAIN CONNECTER.

Application filed December 8, 1927. Serial No. 238,608.

The present invention is directed to improvements in chain connectors.

The primary object of the invention is to provide a device of this character particularly designed for connecting the ends of anti-skid chains used in connection with the tires of automobile wheels.

Another object of the invention is to provide a device of this character so constructed that it can be positively maintained in its operative position to prevent accidental disengagement of the chain from the tire, the construction and arrangement being such that the connector can be easily and quickly manipulated to permit the chain to be removed and replaced on a tire.

In the accompanying drawing:

Figure 1 is a plan view of a section of a skid chain showing the connector in place thereon, one of the connectors being in its operative position and the other about to be placed in its operative position.

Figure 2 is a side elevation of one of the connectors.

Figure 3 is a fragmentary view of a chain and a connector showing it in place upon a section of tire.

Figure 4 is a sectional view on line 4—4 of Figure 1.

Figure 5 is a sectional view on line 5—5 of Figure 1.

The connectors, two of which are employed, consist of a plate 1 having an offset 2 provided with an opening 3, the purpose of which will be later explained. This plate has a keeper 4 adjacent one end and a diagonally disposed open-ended slot 5 adjacent its other end. Carried by the plate 1 in advance of the slot 5 is a headed stud 6.

Cooperative with the plate 1 is a locking lever 7 which has formed adjacent one end thereof a longitudinal slot 8 which opens at each end into laterally disposed recesses 9 and 9', said slot being slidably and pivotally engaged with the stud 6.

The lever is also provided with a diagonally disposed open-ended slot 10, the purpose of which will later appear.

The anti-skid chain includes side chains 11 having one of their terminals connected to the ends of the plates 1, as at 12, there being diagonally disposed chain sections 13 connecting the side chains, the links of the innermost sections being secured in the open-

ings 3 of the offset 2. The other terminals of the chains 11—11 are provided with open links 14 of such size as to freely receive the lever 7 in order that the connectors will unite the terminals of the side chains 11—11.

In Figure 1 one of the connectors is shown locked, or in its operative position, while the other connector is shown in one of its positions during the connecting operation. To connect the terminals of the side chains 11—11 the levers are swung to positions to permit the links 14 to engage thereover, after which the levers are swung towards the plates 1 in order that the links will enter the slots 5 and owing to the diagonal position of the slots 5, as well as the slots 10, the links will be held against accidental disengagement. It will be understood that the levers may be slid downwardly in order to permit the studs to rest in the recess 9', this position being maintained until the levers are substantially parallel with the plates 1, whereupon said levers are moved forwardly until the studs engage the recess 9 and at which time the free ends of the levers have not entered the keepers 4. To engage the levers with the keepers the levers are slid rearwardly so that the free ends thereof will enter the keepers, thus preventing accidental swinging of said levers. When the levers are engaged with the keepers the studs will engage in the recesses 9' which will prevent the levers from sliding forward. In addition to the recesses 9', coacting recesses and projections 15 and 16 are provided, respectively, upon the plates and levers and interlocked in a well known manner.

Having thus described the invention, I claim:

A connector for the terminals of chains of the class described, comprising a plate having a keeper carried thereby, a lever having a slot formed therein provided at its ends with lateral recesses, a stud carried by the plate for pivotally and slidably engaging said slot and capable of seating in the recesses for pivotal movement, said plate and lever having diagonally disposed open-ended slots formed therein for receiving the links of a chain terminal, said lever being slideable relative to the plate for engagement with the keeper carried thereby.

In testimony whereof I affix my signature.
JAMES T. HUTTON. [L.S.]
